UNITED STATES PATENT OFFICE.

CHARLES G. MCKINNEY, OF CHOKOLOOSKEE, FLORIDA.

CAP OR POINT FOR NETTING-NEEDLES.

1,238,314.

Specification of Letters Patent. Patented Aug. 28, 1917.

Application filed January 27, 1917. Serial No. 144,950.

To all whom it may concern:

Be it known that I, CHARLES G. MCKINNEY, a citizen of the United States, residing at Chokoloskee, in the county of Lee and 5 State of Florida, have invented certain new and useful Improvements in Caps or Points for Netting-Needles, of which the following is a specification, reference being had to the accompanying drawings.

10 This invention relates to needles for making and repairing fishing nets and particularly to a needle point for a fishing net needle.

The general object of the invention is the 15 provision of a fishing net needle with a cap or head constituting a point for the needle which is provided with a knife so formed that it may be drawn against the cord to be cut.

20 A further object is to so dispose the knife in the head or cap that the knife will not interfere with the ordinary use of the needle.

Still another object is to provide means whereby the knife may be detachably held 25 within the head or cap so that it may be removed for sharpening and also provide means whereby the knife may be adjusted as it wears.

Other objects will appear in the course 30 of the following description.

My invention is illustrated in the accompanying drawings, wherein—

Figure 1 is a plan view of a netting needle and a cap constructed in accordance 35 with my invention;

Fig. 2 is a plan view of one section of the cap, the other section of the cap being removed;

Fig. 3 is a longitudinal section through 40 the cap and a portion of the needle;

Fig. 4 is a section on the line 4—4 of Fig. 1.

Referring to these drawings, 10 designates the ordinary fishermen's needle which 45 is cut away at 11 and formed with a slot 12 having the central prolongation 13. The needle is to be made either of fine grained wood or of ebonite, hard rubber, or other suitable smooth fine grained material. The

50 cap which is designated generally 13 is approximately arrow-shaped in form and, as illustrated, is formed of oppositely disposed plates riveted together so as to embrace the end of the needle or form a sheath 55 for this end of the needle. This cap is pro-

vided with rearwardly extending laterally disposed prolongations 14 which engage the side edges of the needle end and at its middle the cap is formed with the rearwardly extending prolongations 15 which engage 60 over the middle portion of the needle end, these prolongations being bent toward each other at 16 so as to embrace the needle end at the end of the slot 12. Thus the cap is held firmly but detachably upon the end of 65 the needle.

The cap 13 is preferably made of shear steel or like material and may be made in one piece instead of in two pieces riveted together. At one point on its side edge, 70 the cap is cut away as at 17 and the edges of this cap on both walls of the cap are ground to a shearing edge. Mounted between the walls of the cap is the knife designated generally 18, this knife having a body 75 formed with a blade 19, the knife body being so disposed in the cap that this blade 19 extends down along the cut away portion 17 and so that the back of the blade is approximately in line with the curved edge 80 of the cap. The cutting edge 20 of the blade is rounded and intersects the cutting edges 17^a in the manner shown so that a gradually contracted opening is left between the rear end of the blade and the rear 85 end of the cutting edges 17^a.

The knife is held in place within the cap by a screw 21 extending through the upper and lower walls of the cap. Preferably the upper wall of the cap is formed with a 90 slightly thickened portion 22 which is recessed to provide a countersink for the head of the screw, while the opposite wall of the cap is thickened and perforated for the screw, the perforation being interiorly 95 screw-threaded. The body 18 of the blade is formed with a slot 23 opposite the base of the blade 19 and the opposite walls of the cap are perforated for the passage of a screw 24. Preferably the opposite walls of 100 the cap surrounding the openings for the screw 24 are thickened and the screw is received in a recess or countersink in one of the thickened portions, while the perforation in the opposite portion is interiorly 105 screw-threaded for the screw 21. These screws 21 and 24 act to draw the opposite walls toward each other so as to clamp the knife 18 firmly in place and in its adjusted position. By having the slot 23, it is pos- 110

sible to shift the cutter inward as the cutting edge of the blade wears away and it is possible to detach the screws 21 and 24 entirely and thus allow the cutter to be extracted so that a new cutter may be put in place of an old and worn one.

It will be seen that in the practical use of my invention the blade 19 may be used to cut the twine of a net by drawing the needle 10 backward with a slight jerk, both ends of the twine being taut as the twine always is. As the fishermen always have the knife mounted upon the needle, thus much time is saved and the loss of knives is also saved. 15 The fishermen, in making or repairing nets have to constantly use their knives and a great deal of time is lost in getting the knife out for use and a great many knives are dropped overboard. It will be seen that my 20 combined knife and needle saves time and saves the loss of knives.

Preferably the needle points will be made in three or more sizes to conform to the three or more sizes of needles which are ordinarily used. Inasmuch as these needles are often made by fishermen themselves, it is obvious that the cap may be made and sold separately to be applied to the needles after they are made and furthermore it will be 25 obvious that the knives 18 can be made and sold separately from the caps or points of the needle and be inserted by the fishermen as needed. Of course it is to be understood that this cap or needle point must be as 30 smooth as possible so as not to interfere with the use of the needle and not to act upon the thread when it is being shoved through. Inasmuch as it is rarely necessary to draw back a needle after it is pushed forward, the 35 slight projection of the blade 19 beyond the side edge of the needle point will not interfere with the proper use of the needle.

While I have illustrated a form of my invention which I have found to be very practical and which may be cheaply made, yet it is to be understood that I do not wish to limit myself to the exact form illustrated as minor changes might be made without departing from the spirit of the invention.

50 Having described my invention, what I claim is:

1. A cap or point for netting needles having oppositely disposed parallel walls, the edge of the cap or point being cut away to 55 provide cutting edges, and a knife blade mounted within the cap or point to project through said cut away portion, the knife blade extending toward the rear end of the cap or point, the edge of the knife blade

confronting the cutting edges of the cut 60 away portion.

2. A cap or point for netting needles having oppositely disposed parallel walls, the edge of the cap or point being cut away to provide cutting edges, a knife blade mounted within the cap or point to project through said cut away portion, said knife blade extending with its point toward the rear end 65 of the cap or point, the edge of the knife blade confronting the cutting edges of the 70 cut away portion, and means whereby the knife blade may be adjusted into greater or less contiguity to said cutting edges.

3. A cap or point for netting needles having oppositely disposed walls adapted to embrace the faces and side edges of the netting needle, the side edge of the cap being cut away, a cutting member pivotally mounted within the cap between its walls and having a cutting blade extending through the 80 opening of the cap, the cutting edge of the blade being disposed in convergent relation to the cutting edges formed on the cut away portion of the cap and the knife blade extending with its point toward the rear end 85 of the cap or point, and means for causing the opposite walls of the cap to clamp upon the cutter to hold it in adjusted positions.

4. The combination with a netting needle having a slot adjacent one end, of a cap having oppositely disposed walls joined at their edges and embracing one end of the needle, said cap being approximately arrow-shaped and having medially extending projections having inwardly turned terminations adapted to engage against the end wall of said slot in the needle, the cap being cut away on one side edge to provide cutting edges, and a cutter mounted between the walls of the cap and having a blade extending through the cut away portion of the cap, the cutting edge of the blade being disposed in convergent relation to said cutting edges, the blade extending in a direction away from the point of the cap.

5. A cap or point for netting needles, and a knife blade mounted on the cap, the point of the blade being disposed toward the base of the cap, the back of the knife blade being disposed approximately in line with the corresponding side edge of the cap.

In testimony whereof I hereunto affix my signature in the presence of two witnesses.

CHARLES G. McKINNEY.
